UNITED STATES PATENT OFFICE.

JOSEPH E. TILLMAN AND WILLIAM J. VSETECKA, OF MINNEAPOLIS, MINNESOTA;
SAID TILLMAN ASSIGNOR TO SAID VSETECKA.

KNIFE SHARPENER.

Application filed April 6, 1921. Serial No. 458,956.

To all whom it may concern:

Be it known that we, JOSEPH T. TILLMAN and WILLIAM J. VSETECKA, are citizens of the United States, residing at Minneapolis, 5 in the county of Hennepin and State of Minnesota, have invented certain new and useful Improvements in Knife Sharpeners; and we do hereby declare the following to be a full, clear, and exact description of the 10 invention, such as will enable others skilled in the art to which it appertains to make and use the same.

Our invention has for its object to provide an extremely simple and highly efficient 15 knife sharpener adapted for general use but more especially adapted for use in sharpening carving knives, paring knives and the like.

The improved sharpener is illustrated in 20 the accompanying drawings, wherein like characters indicate like parts throughout the several views.

Referring to the drawings:

Fig. 1 is a side elevation showing the im- 25 proved sharpener;

Fig. 2 is a plan view thereof; and

Fig. 3 is a section on the line 3—3 of 30 Fig. 2.

The sharpening elements of this device 35 are two intermeshing rollers 4 having sharp V-shaped spiral threads 5 held closely in mesh in a suitable holder and capable of intermeshing rotation from time to time as their threads become dulled in spots. As 40 preferably constructed, these rollers 4 are formed with projected trunnions 6 that are rotatively and removably seated in oblique notches or open seats 7 formed in upturned parallel flanges 8 of a flat bearing bar or 45 plate 9 that is preferably extended to form a suitable handle 10 at one end and, at its other end, is turned up to form an end flange 11. It is important to note that the open seats 7 incline toward the end flange 11 and that a clamping screw 12, which works 50 with threaded engagement through said end flange, bears against the adjacent threads of the adjacent roller. When the screw 12 is tightened, it tightly forces the threads of the 55 one roller into the threads of the other, which securely holds the trunnions 6 in their

seats and frictionally locks the two rollers against rotation.

Between the notches 7 and in line with the intermeshing portions of the threads of the 55 two rollers, the side flanges 8 are notched or cut away at 13 to afford clearance for a knife blade 14, (see Fig. 1), that is in position to be sharpened. The handle 10 is shown as provided with perforations 15, 60 through which screws, not shown, may be passed, to anchor the sharpener to a table, shelf or other suitable support.

The spirally threaded rollers are preferably made from tool steel and tempered 65 very hard, but, at any rate, must be made very hard or tempered to a high degree so that the sharp edges of the threads, without becoming quickly dulled, will cut the edge even of a knife that is tempered to a high 70 degree of hardness.

The sharpening of the knife may be quickly dulled, will cut the edge even of a 75 knife that is tempered to a high degree of hardness.

The sharpening of the knife may be quickly produced by placing the edge thereof in contact with the threads of the two rollers at their inner sections and then drawing the knife edgewise across the threads. 80 In this way, a knife may be very quickly sharpened and the sharpening will be very even, because the large number of threads, acting at the same time, prevents chattering or vibration of the knife and, consequently, 85 prevents forming of irregularities or depressions in the sharp edge of the knife.

The threads of the rollers will not become quickly dulled, but, from time to time, new thread surfaces may be brought into position for action by slight step by step rotations of the rollers; and here it is important to note that because of the threaded engagement which causes the two rollers to rotate in mesh with a sort of spiral gear action, rotation of the one roller will cause a corresponding rotation of the other roller and, hence, the threads of the two rollers in use will be worn out or dulled simultaneously.

This sharpener, while of small cost, is of 100 very high efficiency and durable.

What we claim is:

A knife sharpener comprising a holder having laterally spaced side flanges and an end flange, said side flanges having open seats, sharpening rollers having intermeshing spiral threads and also having trunnions rotatably mounted in said open seats and arranged to be lifted therefrom, and a screw

applied through said end flange and operative on the threads of the adjacent roller to 10 frictionally clamp the two rollers together and hold the same in said open seats.

In testimony whereof we affix our signatures.

JOSEPH T. TILLMAN.
WILLIAM J. VSETECKA.
